(57) **CLAIM**

The ornamental design for a display screen with computer generated icon, as shown and described.

DESCRIPTION

The patent or application file contains at least one drawing executed in color. Copies of this patent or patent application publication with color drawings will be provided by the Office upon request and payment of the necessary fee. The sole FIGURE is a front view of a display screen with computer generated icon, showing my new design. The broken lines illustrate the display screen and form no part of the claimed design.
